UNITED STATES PATENT OFFICE.

BENJAMIN H. BEDELL, OF LE ROY, LAKE COUNTY, OHIO.

CLASP.

SPECIFICATION forming part of Letters Patent No. 350,228, dated October 5, 1886.

Application filed May 25, 1886. Serial No. 203,206. (No model.)

To all whom it may concern:

Be it known that I, BENJAMIN H. BEDELL, of Le Roy, in the county of Lake and State of Ohio, have invented certain new and useful 5 Improvements in Clasps; and I do hereby declare the following to be a full, clear, and exact description of the invention, such as will enable others skilled in the art to which it pertains to make and use the same.

10 My invention relates to improvements in clasps, designed more especially for supporting pantaloons from suspenders without the aid of suspender-buttons, and for other similar purposes; and it consists in certain features of 15 construction, and in combination of parts hereinafter described, and pointed out in the claim.

In the accompanying drawings, Figure 1 is a view in perspective showing my improved 20 clasp in position connecting the suspender with the pantaloons. Fig. 2 is an enlarged front elevation of the clasp. Figs. 3 and 4 are elevations in section on the line of xx , Fig. 2, showing, respectively, the clasp closed and 25 open.

The clasp is made of two thin metal plates, A and B, each provided with ears, respectively, a and b , that project substantially at right angles to the respective plates, and are 30 pivoted together at e . The front plate, A, is substantially flat, and has openings A' and A'' , the latter leaving the upper part of the plate in the form of a bail. The plate B below corresponds with the plate A, but above is reduced in width, forming a tongue that is bent 35 forward and made to pass through the opening A'' . The tongue has a part, b' , inclined slightly to the plane of the plate B, and is offset forward at b'' , and from the offset terminates in a thumb-piece, b^3 , the latter overlapping the cross-piece a' at the top of the bail portion of the plate A. The lower part or 40 jaws of each plate are indented from the outside, respectively, at c , causing small projections or teeth on the inside that prevent the 45 jaws from slipping on the cloth. A ring, D, is placed in position, as shown, between the

bail and tongue before the plates are secured on the pivotal wire. The offset portion b'' of the tongue has notches b^4 on either side for engaging the ring D. When the ring is near the pivotal point, as shown in Fig. 4, the jaws may be opened some distance, and in such position may be placed astride the cloth, or a portion of the garment that is to be held, after 50 which, by drawing the ring upward, and by means of the incline b' and the arrangement of parts shown, the jaws are pressed together. When the ring engages the notches b^4 , as shown in Figs. 2 and 3, the jaws are locked and held 55 securely in position grasping the garment. By pressing down on the ring, the tongue being elastic, the jaws are unlocked and may be separated, as in Fig. 4.

The ring D is designed to engage a hook, 6, such as commonly had on suspender-buckles.

In removing the garment the ring is unhooked and the clasp left attached to the garment. The unhooking of the ring is more easily done than unbuttoning suspenders in 70 the usual manner.

The clasps are so small that they may be conveniently carried in the pocket, and in case 75 suspenders are used and one is "lost off" a clasp can be applied in a few moments.

The clasp is recommended especially to bachelors.

What I claim is—

In a clasp, the combination, with plates pivoted together and adapted to grasp and hold 80 the material, one of said plates having a bail integral therewith, and the other plate having a tongue inclined and offset, as shown, and extending through the opening in the bail, of the ring operating between the tongue and 85 bail, substantially as set forth.

In testimony whereof I sign this specification, in the presence of two witnesses, this 20th day of May, 1886.

BENJAMIN H. BEDELL.
